ELECTRICAL INDICATING MEANS

William F. Quinby, Long Island City, N. Y., and
 John A. Herbst, Galion, Ohio, assignors to The
 Teleregister Corporation, New York, N. Y., a
 corporation of Delaware

Application March 1, 1939, Serial No. 259,238

11 Claims. (Cl. 177—353)

This invention relates to electrical indicating means and more particularly to indicating or signaling apparatus and methods, according to which indicating devices corresponding to a large number of different items may be operated at various receiving stations and all controlled over a single wire or a small number of wires from a signal transmitting station.

While not limited thereto, the invention is particularly adaptable to the transmission and posting of varying quotations or prices of a multitude of items such as stocks, bonds, commodities and the like. The transmission of the quotation signals is from the transmitting station which may be located within a stock exchange or connected thereto by suitable signaling circuits, and arrangements are provided whereby quotation service is provided to a large number of brokers or others, this service relating to as many of the stocks or other items as are of particular interest to the subscriber at each receiving station.

In systems of this character heretofore devised the receiving apparatus at the subscriber's station is complicated in structure, expensive to install and difficult to maintain in operation. The present invention provides a receiving mechanism which is relatively inexpensive to install and, because of the specific construction and arrangement of the circuits employed, is adapted to give reliable and satisfactory operation in service at high speeds, and over long periods of time, with a minimum amount of maintenance and fine adjustments required.

The objects of this invention include the provision of apparatus of the above indicated class which will be rapid, accurate and dependable in operation and which is adapted to be operated by signals received over a single line wire.

Another object of the present invention resides in the provision of a novel arrangement of distributor structure which receives the incoming quotation signals and retransmits the price signals thereof for actuating the indicators of the selected stocks or items to their new settings in such manner that the price signals are retransmitted invariably in proper phase relationship with respect to the incoming quotation signals.

Another of the objects of the invention resides in the provision of means in the receiving apparatus for regenerating the signals received from pulsing segments of the receiving distributor and applying the regenerated signals to the

selected stock indicators under control of the quotation signals received by the distributor.

A further object of the invention resides in the combination of a single set of price storage overlap units in a receiving mechanism adapted to receive signals over two channels of communication and circuit means including contacts of the price storage overlap units for transmitting operating impulses to the indicators of both channels.

Another object resides in the provision of stock quotation receiving apparatus in which multiple range selection is effected with a smaller number of range selecting relays than has heretofore been possible with systems employing range selecting relays.

A further object resides in preventing false operation of the regenerative mechanism in an item quotation system, as, for example, when the signals received do not relate to one of the items posted.

Another object resides in the provision of means for operating a plurality of quotation boards, each comprising a plurality of groups of indicators, by means of a single receiving mechanism of the character herein described.

Other objects, features and advantages will more clearly appear from the following description when taken in connection with the accompanying drawings and the appended claims.

The invention resides in the novel signalling features, methods and combinations of circuits and parts as hereinafter described by way of example only, as being illustrative of a certain preferred embodiment of the invention.

In order that the invention will be more fully understood, reference will be had to the accompanying drawings in which Figs. 1 to 4 represent the apparatus and circuits at the receiving station responsive to permutation code signals received over a line for converting these signals into selection and indicator operating impulses and applying these signals thus converted to a plurality of quotation boards over two channels of communication.

Figs. 5, 6 and 7 show the plan, front and side elevation respectively, of an overlap unit suitable for use with the system.

Fig. 8 represents a set of signals received by the distributor during one revolution thereof.

Fig. 9 is a diagram showing the relation of the quotation signals received during successive revolutions of the distributor to the indicator operating impulses.

Fig. 10 shows a suitable code for the stock number selection.

Fig. 11 shows a suitable code for price selection.

Fig. 12 shows a suitable code for range selection.

Description of selector

The apparatus and circuits of the receiving mechanism shown on Figs. 1 to 4 will now be described. Fig. 1 shows the polarized line relay and distributor RD for receiving the line signals and for generating indicator operating impulses. Connected to the receiving distributor is a stock selection over lap unit settable in accordance with the selection signals received and a price overlap unit settable in accordance with the signals representative of the price portion of the quotation. The receiving distributor is also connected to a group of range relays for storing and decoding the range signals received. A stock selector is operatively connected to the stock selection overlap unit and takes settings in accordance with the signals stored in the selection overlap unit. A group of price relays, designated P1 to P4, is connected to the price overlap unit in such a manner that the operation of any selection contact of the price overlap unit completes a circuit to a contact of one of the price relays P1 to P4, whereby the drums of the selected indicators are moved into positions in accordance with the price signals received by the receiving distributor.

The receiving distributor RD is provided with three distributor rings designated R1, R2 and R3. Certain segments of the ring R1 are employed for receiving the quotation signals. Interspersed with these receiving segments on the ring R1 are four groups of transmitting segments which cause impulses to be transmitted to the indicators of the selected stock for posting the stock price. Segments 2, 8, 40, 46, 52, 58 and 64 are connected together in such a manner that seven impulses are transmitted to the selected indicators when this group is selected for operation during the time that these segments are traversed by the distributor brush DB. Segments 6, 59, 56 and 62 are connected together to transmit four impulses as the segments are traversed by the brush DB. The third group of segments transmits two impulses for operating the indicators, this group comprising segments 20 and 26 whereas the segment 14 of the ring R1 controls the transmission of a single impulse to the selected indicators.

When the indicators are first selected for operation, a series of 10 impulses are transmitted to the indicators to restore them to their normal or blank settings. The fourth group of segments 4, 10, 16, 22, 28, 34, 48, 54, 60 and 66 of the ring R1 are connected together and are employed for initiating these ten restoration impulses.

This distributor structure comprising a series of segments for receiving the incoming quotation signals and another series of segments interspersed with the receiving segments for actuating the selected indicators, provides an arrangement whereby the indicator actuating impulses are invariably transmitted in the proper phase relationship with respect to the incoming quotation signals. The indicators are thus reliably operated by the impulses received by the transmitting means and the system is free from the defects of other quotation systems of this character wherein the impulse generating means is not embodied in the receiving distributor ring and traversed by the same brush that traverses the

receiving segments, such as, for example, the failure of the impulse generating means to start into operation or to be set into operation at the proper time with respect to the incoming quotation signals received by the receiving distributor or, having once been set into operation, to complete its cycle of operation at the proper time with respect to the incoming quotation signals received.

In high speed stock quotation systems such as are adapted to meet the requirements of brokers and others trading on the New York Stock Exchange, it is essential that the timing of the various mechanisms be closely controlled in order that reliable and accurate service may be furnished, notwithstanding the very high speeds at which the system necessarily operates. It is important that the timing and operating limits of the various parts comprising the receiving and retransmitting mechanism of the system be determined and maintained by means of the physical structure of the mechanism itself, rather than by the skill and judgment of installation and maintenance men. The distributor arrangement disclosed herein comprises one of the various features of our system illustrative of such an arrangement.

The quotation boards are of the general type described in a patent to Haselton et al. No. 1,890,878, granted December 13, 1932. Briefly, such a board comprises a multitude of indicators arranged in groups of 20, each of such groups representing a single stock or item and is divided into five sets or levels of four indicators each for posting the "yesterday's close," "open," "high," "low," and "last" ranges of the stock. The four indicators of each set enable the hundreds, tens, units and fractions portion of the price to be displayed. The indicators are of the well known step-by-step type requiring normalization to the blank position prior to actuation to the proper digit display position thereby to avoid a possible accumulation of errors when changing from one price setting to the next succeeding price setting.

Fig. 2 shows a group of range selection relays employed with channel 1 quotations and a second group of range relays employed for quotations on channel 2. Fig. 2 also shows two sets of regenerator units, there being one set for each of the two channels of communication. Each set comprises three regenerator units which are employed normally for operating the tens, units and fractions indicators of the selected stock. Each regenerator unit comprises the relays A and AA; as for example, for operating the indicator units in accordance with the value of the tens digit of the selected stock. The term "regenerator" or "regenerator unit", as herein referred to, shall be defined as comprising relays A and AA together with an interconnecting circuit and may be of the type disclosed on Patent No. 1,965,377, issued July 3, 1934 to R. M. Hicks et al. The purpose of the regenerator unit is to provide signals of predetermined constant length for the operation of the indicator units and thus insure reliable operation of the indicator units at the rapid rate of posting quotations for which the present system is adapted.

Fig. 3 shows the indicators and selection relay for one of the plurality of stocks posted on the main display board, together with the switching mechanism for controlling the operation of the indicators over either of the two channels of communication. Fig. 3 also shows various relays employed with the system for controlling certain

features thereof; as for example, the channelling, synchronizing and rewrite features, as will be more fully described hereinafter.

Fig. 4 shows the indicator units and selection relay for one of the items posted on the auxiliary quotation board and the switching mechanism associated therewith for controlling the operation of the selected indicators over either of the two channels of communication. There is also shown on this figure the regenerator units for operating the indicators of the selected items. Fig. 4 also shows the range selection relays for channel 2 quotations, the corresponding range relays for channel 1 quotations being shown on Fig. 2 of the drawings.

The relation of the quotation signals received by the distributor RD to the restoration and actuation indicator operating impulses for channel 1 and channel 2 quotations is illustrated on Fig. 9 of the drawings. Referring to the illustration of Fig. 9, it will be noted that each quotation is composed of four parts: stock number and range selection, restoration and actuation of the selected indicators, the transmission of the entire quotation to the display board occurring during three revolutions of the receiving distributor RD. The quotation signals received by the distributor RD during one revolution thereof comprises the stock number, range and price characteristics of the quotation. These quotation signals are received and stored in the selector while restoration and actuation impulses corresponding to a previous quotation are being transmitted to the selected indicators. The line signals for a complete quotation are received during a single revolution of the distributor RD and concurrently with the reception of these signals the stock selection is effected and restoration impulses are transmitted to the indicators of the selected stock. These restoration impulses continue during part of the second revolution of the receiving distributor thereby causing the selected indicators to be restored to normal. After this has been effected, and while the second revolution of the receiving distributor is still in progress, actuation impulses are transmitted to the selected indicators to actuate them to their new settings in accordance with the price signals received during the first revolution of the distributor. The actuation impulses continue during part of the third revolution of the receiving distributor in accordance with the numerical value of the price signals received. The indicators are operated by impulses from the regenerator units which are operated from certain segments of the receiving distributor ring R1 through the action of pulsing relays, as will hereinafter be described in greater detail.

During the first revolution of the distributor RD the signals received relate to a stock posted on channel 1, whereas during the second revolution of the distributor the received signals relate to a channel 2 stock. During each odd numbered revolution of the distributor RD the reception of signals for a channel 1 quotation is received and during each even numbered revolution, the distributor receives signals for a channel 2 quotation. During the second revolution of the distributor RD, while restoration and actuation impulses are being transmitted to the selected indicators of the channel 1 stock which was selected during the first revolution of the distributor RD, the signals for a channel 2 stock are received. While the signals for the channel 2 stock are being received, the indicators of the channel 2 stock are selected and receive restora-

tion impulses, these impulses continuing while signals for the second channel 1 stock are received during the third revolution of the distributor RD. The actuation impulses for the channel 2 stock continue during part of the fourth revolution of the receiving distributor while quotation signals for the second channel 2 stock are being received.

The transmitter suitable for operation with the system may be as shown in an application of W. F. Quinby, Serial No. 55,510, filed December 21, 1935 for Signalling systems, or in accordance with an application by W. F. Quinby, Serial No. 167,541, filed October 6, 1937, for Transmitting means, now Patent No. 2,187,892 dated January 23, 1940. In the aforesaid systems different code combinations are employed for the selection digit 1 and the price digits 9 and 0 than are employed in the present system. In the system shown in application, Serial No. 55,510 the only changes in the transmitting equipment are a rearrangement of the key designations whereby the selection key which causes a signal to be transmitted comprising the code units marking, marking, spacing, marking should be designated 1 and the keys which cause price signals to be transmitted comprising the code units marking, spacing, marking, spacing and marking, spacing, marking, marking should be designated 9 and 0 respectively. Whereas in the system disclosed in application, Serial No. 167,541, the hundreds stock number coding relay for the digit 1 is so arranged that it causes the transmission of a signal comprising the code units marking, marking, spacing, marking instead of marking, marking, spacing, spacing and a rearrangement of the key designations whereby the operation of the price digit key 9 causes a signal to be transmitted comprising the code units marking, spacing, marking, spacing and the price digit key 0 the code units marking, spacing, marking, marking.

The receiving distributor RD performs three functions, the first of which is to receive the line signals on the odd numbered segments 1 to 65 of the ring R1. Of these segments, the segment 1 is employed for operating the start magnet SM of the distributor and thus causing the release of the distributor brush DB for operation under control of the line relay LR. The odd numbered segments 3 to 25 are connected to the selection magnets of the stock overlap unit, segments 3, 5, 7 and 9 being employed for the hundreds digit of the stock number, segments 11, 13, 15 and 17 for the tens digit and segments 19, 21, 23 and 25 for the units digit of the stock number. The odd numbered segments 27 to 35 are employed for controlling the posting of rewrite quotations of the quotation board, as will be hereinafter explained in greater detail. Segments 37, 39, 41 and 43 are connected to the operate winding of the range storage relays R1 to R4 respectively. Segments 45, 47, 49 and 51 are employed for receiving the tens digit of the price, segments 53, 55, 57 and 59 receive the signals for the units price digit and segments 61, 63 and 65 the fractions price digit signal. The odd numbered segments 45 to 65 are connected to the selection magnets of the price overlap unit POU.

A second function of the distributor RD is to provide a source of impulses for causing the selected indicators to be restored to their normal positions and thereafter step ahead to the new price positions. These impulses are generated by the brush DB passing over certain of the even numbered segments of the ring R1, as will

be clearly apparent as the description proceeds.

A third function of the distributor RD is to time the operation of that portion of the receiver which decodes the quotation signals in order that the decoding process may start as soon as sufficient line signals have been received, and furthermore, that the various decoding operations follow each other in such timed relationship as to enable the receiver to operate in a manner as to make the most efficient use of the time allotted to each quotation.

The overlap unit mechanism shown diagrammatically on Figs. 1, 5, 6 and 7 of the drawings is employed to store the incoming signals representing the stock number and price of a quotation while at the same time receiving and storing stock number and price signals of a next succeeding quotation. Whereas two such overlap units SOU and POU are shown on the circuit diagram of Fig. 1 for receiving and storing stock selection and price signals respectively, it will be understood that a single overlap unit may be employed for receiving and storing these signals. The stock selection overlap unit comprises twelve selection magnets 11 which are employed for the stock number and the price overlap unit comprises eleven such selection magnets, each of the magnets having two windings 11-A and 11-B. As shown in detail on Figs. 5, 6 and 7, the selection magnets 11 are mounted preferably adjacent to one another and in a single horizontal row on the plate 12 in any well known manner having a portion 13 thereof set parallel with, and in the direction of, the magnet 11. Associated with each magnet 11 is an armature 14 which is pivoted at 15 and normally rests against the backstop 16. A member 17 holds loosely the armature 14 against the pivot 15.

Each of the magnets 11 upon energization of its operate winding 11-A attracts its armature 14 thereto, and causes the contact spring 18 to be operated and make contact with spring 19, these springs 18 and 19, as well as springs 21 and 22 which comprise the pileup 23, being normally electrically separated from one another by suitable insulating material 24. Now referring to Fig. 1 it will be seen that springs 18 and 19 of the various magnets 11, in closing, connect ground to one end of the associated locking windings 11-B thus locking up the armatures 14 (Fig. 7) of the energized magnets 11.

Referring to Fig. 7 it will be noted that an armature 14, when attracted by its associated magnet 11, causes the insulator 25 to thrust upward against the spring 21 so that its contact engages with that of spring 22. This function, however, is prevented by the bar 26 which restrains the upward movement of the spring 21. After the various magnets 11 have been energized to store the code signal of a quotation, the magnets 27 attract their armatures 28 thereby withdrawing the bar 26 from engagement with the several springs 21.

Withdrawal of the bar 26 from engagement with the spring 21 permits each of those springs whose associated armature 14 is being attracted by its magnet 11 to be forced upward so that the contact of spring 21 engages with that of spring 22. Those springs 21 and 22 whose contacts have become engaged with one another are maintained in that position after their magnets have become deenergized by the subsequent return of the bar 26 to its normal position. In the event that some of the springs 21 and 22 have been previously held in the operated posi-

tion by the bar 26, the operation of this bar will permit the springs 21 to return to their normal positions provided, however, their associated magnets 11 are not energized, in which latter case each of the energized magnets 11 will attract its armature 14 thus holding operated the associated springs 21 and 22.

As the magnets 27 become deenergized, armatures 28 under tension of springs 29 return to rest against the stop screws 31, thus returning bar 26 to its normal position. The bar 26 having returned to its normal position, holds operated those springs 21 and 22 which were operated by the energization of their individual magnets 11, and prevent those springs 21 which are not in engagement with springs 22 from becoming so engaged by the subsequent operation of their armatures 14 until such a time as the bar 26 is again withdrawn from engagement with the several springs 21.

Each overlap unit also comprises a pair of normally closed contacts 32 and 33. These contacts are supported by springs insulated from one another and from a supporting member 34 by suitable insulating material 35.

Springs 32 and 33 are controlled by a latch 36 which is joined to the bar 26 by a hinged pin 37. The latch 36 is under tension downward and is held against the eccentric adjustment screw 38 by the action of the spring 39. Movement of the latch 36 to the left by action of the bar 26 causes the inclined portion 41 of the latch 36 under tension of the spring 39 to slide downward on the screw 38 thus causing the left end of the latch 36 to be lowered.

As latch 36 continues to move to the left, a tip 42 rides over the top of spring 43.

As herebefore stated, the bar 26 in moving to the left allowed the springs 21 whose associated armatures 14 were being attracted by their magnets 11, to operate, and those springs 21 whose associated magnets 11 were deenergized, remained unoperated or returned, if previously operated, to their normal unoperated positions. As the bar 26 returns to its normal position to maintain the various springs 21 in the position in which they have been operated by the magnets 11, the latch 36 is moved to the right. As the latch 36 moves to the right the tip 42 engages the spring 43 and moves it together with the insulator 44 and spring 32 to the right, thus disengaging the contacts of the latter spring from that of spring 33.

Referring to Fig. 1, it will be seen that the opening of contacts 32 and 33 removes ground from the contacts 19 of the magnet 11 of the overlap unit thus causing the deenergization of any of the magnets 11 and release of their armatures 14 which may have been operated and whose springs 21 and 22 are now held engaged by the bar 26.

As latch 36 continues to move to the right, the inclined portion 41 rides upward on the screw 38 thereby causing the left end of latch 36 to move upward and disengage the tip 42 from the spring 43 thus allowing the contacts of springs 32 and 33 to again close to supply ground to the springs 19 for locking the magnets 11 when subsequently operated.

The function of the stock selector indicated diagrammatically on Fig. 1 within the dotted rectangle S, is to receive the stock number in numerical code from the overlap unit and to close a pair of contacts thereby to cause the operation of a stock relay and select the indicators of the desired stock which may lie within either the

channel 1 or channel 2 section of the display board.

In the specific embodiment of the invention shown on the drawings each stock is represented by a three digit number, the stock numbers being duplicated on each of the two channels thus providing a system adapted to post the prices of 2000 different stocks. The stock selection equipment has for its essential feature a set of notched code bars 45 similar to those used in certain of the well known telegraph printers which have been in commercial use for several years. The code bars 18 are arranged in three sets of four each and include a channel code bar, and these bars take settings under control of the selection magnets corresponding to line impulses received for a stock abbreviation and also in accordance with whether the price of a first or second channel stock is to be posted. Each stock abbreviation usually comprises three characters each represented by a four unit permutation code and the twelve code impulses or spaces thus received determine the selection of the particular code bars 45 to be operated, the thirteenth code bar automatically taking its setting under control of local circuits in accordance with whether the stock to be selected is situated within the channel 1 or channel 2 section of the board.

Located transversely to, and above the thirteen code bars are any desired number of stock bars 46, there being preferably one hundred stock bars for each unit of the equipment and as many units as are required for the number of stocks to be posted. Each of these stock bars is so notched with respect to the thirteen code bars that a particular setting of the code bars is required to permit it to move parallel to its length under control of the usual coil spring. Thus, for every possible setting of the code bars as determined by the line impulses for a stock abbreviation and whether it is a first or second channel quotation, there is one corresponding stock bar which will move after the stock abbreviation and channel information has been received and the code bars set. In moving, the stock bar closes a pair of electrical contacts individual to each stock bar thereby applying battery to the winding of the selected stock relay to cause it to operate and connect the indicators of the selected stock to their pulsing circuits.

When the selection overlap unit operates, battery is connected to the selected ones of the various selection magnets S1D, S2D and S3D of the stock selector S. As indicated on Fig. 1, the circuit for these magnets is closed at the time the storing of the stock number selection information has been completed. After these magnets have been energized and have operated their associated code bars 45, the selected stock bar 46 will move to the right and apply battery to the coil of the stock relay of the particular channel in accordance with the operated condition of the selection magnet CH of the stock selector.

The operation of the various circuits of the selector shown in Figs. 1 to 4 will now be explained. The operation of the selector will best be understood by consideration of a particular example. Let it be assumed, therefore, that signals indicative of a quotation for a channel 1 stock having a stock number 123, Unison range 70 and a price of 98 1/2 were transmitted to the line relay LR over the line 51 thereby causing the tongue of the line relay to be moved into engagement with contact M or S in accordance with whether the incoming line signal is marking or

spacing in character. Whereas one end of the winding of the line relay LR is shown connected to ground, it will be understood that several line relays may be connected either in series or in parallel, as is well known in the telegraph art thereby enabling several selectors to be operated simultaneously under control of signals received over a single circuit. In the following description it will be understood that very frequently 10 more than one of the circuits are completed simultaneously whereas in describing the same it will, of course, be necessary to describe them successively.

During the time that quotation signals are not 15 being transmitted over the line 51, the polarized line relay LR receives a marking signal and maintains its armature against the contact M. When quotation signals are to be received by the line relay, spacing battery is applied to the line 20 51 causing the tongue of the line relay LR to move into engagement with the contact S, thereby applying battery to the start magnet SM from whence the circuit is continued through segments 1 of the ring R1, brush DB and ring R2 to ground. The start magnet operates and attracts its armature 52, thereby releasing the brush DB for one revolution. During the operation of the receiving distributor the line relay is moved from marking to spacing in accordance 25 with the line signals received. The first four signals received following the start signal are employed for selecting the hundreds digit of the stock number, the next four signals the tens digit and the next succeeding four signals the 30 units digit of the stock number, the stock number selection signals being in accordance with the selection code shown on Fig. 10 of the drawings. Following the twelve code unit signal employed for stock selection, is a five unit signal for controlling the selective operation of the subscriber's board, as will more clearly appear as the description proceeds. Following this signal is a four unit code signal for selecting the group of indicators corresponding to the range or ranges of a 35 selected item in accordance with the code arrangement shown on Fig. 12. Following the range selection signals is a four unit code signal employed for selecting the tens digit of the price, a four unit signal for the units digit and, lastly, 40 a three unit signal for the fractions digit of the price. A code suitable for the price information is shown on Fig. 11 of the drawings.

In the example assumed, the hundreds digit of the stock number is 1, and therefore units 1, 2 45 and 4 will be marking and unit 3 of this signal will be spacing in character. During the time that the brush DB is in engagement with segment 3 of the ring R1, the tongue of the line relay will be in engagement with the marking 50 contact M and battery will be applied to conductor 53 extending to the first selection magnet 11 of the selection overlap unit SOU from whence the circuit is continued through segment 3 of the ring R1, brush DB and ring R2 to ground, thereby causing this selection magnet 11 to operate through the action of its winding 11A and close a locking circuit comprising battery and armature 32 of the overlap unit SOU, contact 33, conductor 54, winding 11B of the selection magnet 11, contacts 18 and 19, conductor 55, and thence to ground thereby maintaining the magnet 11 energized after the brush DB has moved out of engagement with segment 3 of the ring R1.

During the time the brush DB is in engagement with segment 5 of the ring R1 the tongue

of the relay LR is against the marking contact thereby applying battery to conductor 53 and operating the second selection magnet 11 of the overlap unit SOU over a circuit including segment 5 of the ring R1, brush DB and grounded ring R2. This second selection magnet also locks to battery on conductor 54 in a manner similar to the locking of the first selection magnet 11.

During the time that brush DB is in engagement with segment 7 of the ring R1, the tongue of the line relay is resting against the contact S and battery is thus removed from conductor 53 thereby preventing the operation of the third selection magnet 11. When the brush DB is in engagement with segment 9 of the ring R1, the tongue of relay LR is against the marking contact M and the fourth selection magnet is therefore operated. The code signal corresponding to the hundreds digit of the stock number has now been received and stored in the selection magnets of the overlap unit SOU.

When the distributor brush engages segment 11 of the ring R1, the line relay is in the marking position thereby causing the operation of the associated selection magnet 11.

When the brush is in engagement with segment 13 of the ring R1 the line relay is in the spacing position and the associated selection magnet 11 is, therefore, unoperated. During the time segment 15 is being traversed by the brush DB the line relay is in the marking position and the associated selection magnet is operated. The selection magnet associated with segment 17 of the ring R1 is unoperated as during the time ground is applied to this segment by the brush DB, the line relay is in the spacing position. The tens digit 2 of the stock number having the code units 1 and 3 thereof marking and the units 2 and 4 spacing in character have now been stored in the selection overlap unit SOU.

Similarly, as the distributor brush passes over the group of segments 19 to 25 the selection magnets associated with segments 19 and 25 are operated and the selection magnets associated with segments 21 and 23 are unoperated thereby storing the units digit 3 of the stock number having the code units 1 and 4 thereof marking. The entire stock number is now stored in the selection magnets of the selection overlap unit.

Since in the example assumed, the selective rewrite operation of the subscriber's equipment was not included, the line relay will receive spacing impulses during the time that the distributor brush traverses segments 27, 29, 31, 33 and 35 of the ring R1. As segment 37 of the ring R1 is traversed by the brush DB, ground is applied to conductor 3 of cable 56 extending to one end of the operate winding of relay R1, the other end of this winding being connected by conductor 53 to the contact M of the line relay LR. Since in the example assumed the signals for a unison range are being received, code unit 3 will be marking the code units 1, 2 and 4 spacing in character. At the time that the distributor brush is in contact with segment 37 of the ring R1, therefore, the tongue of the line relay will be against the spacing contact thereby removing battery from conductor 53 and preventing the operation of the relay R1. With the distributor brush in engagement with segment 39 of the ring R1, ground is applied to conductor 4 of cable 56 and thence to one end of the operate winding of the range relay R2, the other end of the relay winding being connected by means of conductor 53 to the marking contact of the line re-

lay. Since the second unit of the code for the unison range is spacing in character, the tongue of the relay LR will be disengaged from its contact M and relay R2, therefore, will not be operated.

With the distributor brush in engagement with segment 41 of the ring R1, ground is applied to conductor 5 of cable 56 extending to the winding of relay R3 from whence the circuit is continued by way of conductor 53, contact M and armature of line relay LR to battery causing relay R3 to operate and lock by way of its make contact and armature 57, conductor 58, armature 59 and break contact of relay RLS-1 and thence to battery. As the distributor brush engages segment 43 of the ring R1, ground is applied to conductor 6 of cable 56 and thence to the winding of relay R4, the other end of the relay winding being connected to contact M of the line relay by way of conductor 53. Since the fourth unit of the unison code is spacing, battery is not applied to contact M of the line relay LR and the range relay R4, therefore, does not operate. The signal for unison range is now stored in the group of range relays R1 to R4.

The signals for the first unit of the coded signal corresponding to the tens digit 9 of the price is received during the time that the distributor brush DB is in contact with segment 45 of the ring R1. Since this unit is marking in character, the line relay applies battery to conductor 53 extending to the winding 11A of the first selection magnet of the price overlap unit POU from whence the circuit is continued to segment 45 of the ring R1, brush DB and grounded ring R2 of the distributor thereby causing this selection magnet to operate and complete a circuit from grounded conductor 55, contacts 19 and 18 of the selection magnet, winding 11A thereof, conductor 61, contacts 32 and 33 of the overlap unit POU and thence to battery thereby maintaining the selection magnet 11 energized after the distributor brush has passed beyond segment 45 of the ring R1. As the distributor brush passes over segment 47 of the ring R1, the second selection magnet 11 is not operated as the tongue of the line relay is resting against its spacing contact at this time. As the distributor brush passes over segment 49 of the ring R1, the third selection magnet of the overlap unit POU is operated as the tongue of the line relay is resting against its marking contact during this time. When the distributor brush engages segment 51 of the ring R1, the tongue of the line relay is resting against the contact S and the fourth selection magnet is, therefore, not operated. The signal for the tens digit 9 of the stock price has now been received and stored in the price overlap unit.

As the distributor brush engages segment 53 of the ring R1, the fifth selection magnet of the overlap unit is operated by the line relay LR engaging its marking contact. During the time that the distributor brush was crossing segments 55 and 57 of the ring R1, spacing signals were received by the line relay and the associated selection magnets 11 therefore are not operated.

When the distributor brush engages segment 59 of the ring R1, the tongue of the line relay will be resting against its contact M and the eighth selection magnet of the price overlap unit will, therefore, be operated. The signal for the units digit 8 has now been received and stored in the overlap unit POU.

As the distributor brush engages segments 61,

63 and 65 of the ring R1, the line relay is receiving marking impulses and, therefore, applies battery at the armature thereof to conductor 53 causing the last three selection magnets of the price overlap unit to be operated to store the fractions digit 7/8. Each of the selection magnets 11 of the overlap unit POU, when operated, locks by means of its winding 11B and contacts 18 and 19 to the grounded conductor 55 and the conductor 61 under control of the contacts 32 and 33 of the overlap unit to battery. The selection and price signals for a complete quotation have been received and stored during this first revolution of the distributor RD.

When the distributor brush DB engaged segment SS of the ring R3 during this first revolution of the distributor, ground was applied to the winding of relay SS causing the relay SS to operate and move its armature 62 into engagement with the make contact thereof, thereby applying battery to conductor 63 extending to the clutch trip magnet CTM of the stock selector S. The stock selector may be any of the types suitable for the purpose, several of which are well-known in the art, and may generally correspond to the mechanical stock selector unit illustrated and described in the patent to Hicks et al., No. 2,162,170, issued June 13, 1939. The magnet CTM operates over the circuit just described thus setting the stock selector S into operation to actuate its contact and reset bail thereby to cause the selected stock bar to move and close its pair of contacts in accordance with the settings of the selection magnets of the groups SID, S2D, S3D and the CH selection magnet. Although the stock selector clutch shift magnet operates at this time, the selected stock bar does not move to its operated position until after the selection bars have taken their settings, as is well known in selectors of this type. Various details of construction which may be utilized in such selectors are disclosed in the patent to Krum et al. 2,147,656 and the patent to Morton 2,209,802.

When the distributor brush DB engages segment CH of the ring R3, ground is applied to conductor 2 of cable 64, armature 65 and break contact of relay CH2, operate winding of relay CH1, break contact and armature 66 of relay SYN to battery thereby causing relay CH1 to operate and move its armature 67 into engagement with the contact thereof. When the distributor brush leaves segment CH of the ring R3, ground is removed from conductor 2 of cable 64 thereby causing relay CH2 to operate over the following circuit: Battery at armature 66 and 55 break contact of relay SYN, winding of relay CH1, make contact and armature 67 of relay CH1, winding 68 of relay CH2 to ground. When armature 70 of relay CH2 engaged its make contact, battery was applied to conductor 14 of cable 60 69 thereby causing relay TR1 to operate and thus select the range relays of channel 1 for operation.

When the distributor brush engages segment RLS of the ring R3, ground is applied to conductor 3 of cable 64 extending to one end of the winding of relay RLS, the other end of this winding being connected to battery. Relay RLS operates and moves its armature 68 into engagement with the make contact thereof thereby applying battery to conductor 13 of cable 69 extending to the trip magnets 27 of the overlap units SOU and POU thereby causing the trip magnets to operate and transfer the settings of the selection magnets 11 to their associated contacts

21 and 22. With the contacts 21 and 22 in engagement with one another, a circuit is closed from battery at armature 71 of relay RLS and make contact thereof, conductor 1 of cable 69 extending to the contacts 21 of the selection overlap unit SOU from whence the circuit is continued by the operated ones of these contacts and their associated contacts 22 to the selection magnets SID-1, SID-2, S2D-1, S2D-3, S3D-1 and S3D-4 of the stock selector S, the other end of the windings of these selection magnets being connected to ground. These selection magnets operate and attract their armatures thereby causing their associated selection bars 45 to be moved by the reset bail to the operate position. The operation of relay RLS at its armature 71 connected battery to armature 72 and make contact of relay CH2, conductor 2 of cable 69 extending to the selection magnet CH of the stock selector S thereby operating the selection magnet CH and thus causing its selection bar to be moved to the operate position since, in the example assumed, the stock to be selected lies within channel 1. The selection signals for the stock 123 of channel 1 have now been transferred to the stock selector and the selected stock bar will be moved by the contact bail of the stock selector to close its associated contacts during the time that the rewrite signal is being received and not later than the time when the distributor brush engages segment LC of the ring R3. The closure of the contacts 85 and 86 of the stock selector S completes a circuit from battery at armature 82 and break contact of relay RR1, armature 83 and break contact of relay RLS-1, resistance R, conductor 80, contacts 85 and 86 of the selected stock bar, conductor 1 of cable 87, winding of the stock relay G and thence to ground. The resistance R is sufficiently high in value to prevent the operation of the relay G, the flow of current through the winding of the relay G being employed to cause the relay to operate very quickly after the resistance R is short-circuited by the operation of the relay LC1 or LC2, as the case may be.

As the distributor brush DB leaves segment RLS, relay RLS releases. When the distributor brush engages segment TR of the ring R3, ground is applied to conductor 4 of cable 64, armature 73 and break contact of relay TR3, winding of relay TR2, break contact and armature 74 of relay TR3 to battery causing relay TR2 to operate and at its armature 75 and make contact apply battery through resistance 76 to winding 77 of relay TR3. However, ground on conductor 4 of cable 64 is applied by way of armature 90 and break contact of relay TR3 to one end of winding 77 of relay TR3, which does not operate at this time due to the application of ground to both ends of its winding 77. When the distributor brush DB leaves segment TR ground is removed from conductor 4 of cable 64 and relay TR3 operates from ground through the winding 77 of relay TR3, resistance 76, make contact and armature 75 of relay TR2 to battery.

When the distributor brush engages segment LC of the ring R3, ground is applied to conductor 5 of cable 64, armature 79 and make contact of relay CH-2 and thence to the winding of relay LC1 thereby causing relay LC1 to operate and at its armature 81 complete the following circuit: Battery at armature 82 and break contact of relay RR-1, armature 83 and break contact of relay RLS-1, conductor 7 of cable 69, armature 84 and make contact of relay CH-2, armature

81 and make contact of relay LC1, conductor 3 of cable 69, contact spring 85 and contact 86 of the operated stock bar 46 of the stock selector S, conductor 1 of cable 87, winding of the stock relay G and thence to ground. The stock relay G operates over the circuit just described thereby selecting the indicators of the stock 123 for operation. The relay G remains locked after the stock selector bar has restored over the following circuit: Ground, winding of relay G and make contact 88 thereof, contact 89 of the slidable member 91, conductor 2 of cable 92, armature 93 and make contact of relay LC1, locking winding of relay LC1, break contact and armature 94 of relay CH-1 in parallel with break contact and armature 71 of relay RLS and thence to battery. Relay LC1 is thus held locked in series with the winding of the selected stock relay G over the circuit just described after the distributor brush DB has left segment LC of the ring R3. The operation of relay LC1 at its armature 95 completed a circuit from battery at armature 82 and break contact of relay RR-1, armature 83 and break contact of relay RLS-1, conductor 7 of cable 69, armature 84 and make contact of relay CH-2, armature 95 and make contact of relay LC1, conductor 6 of cable 69, conductor 96, armature 97 and break contact of relay R1, armature 98 and break contact of relay R4, armature 99 and make contact of relay R3, conductor 3 of cable 101, armature 102 and make contact of relay TR1, conductor 3 of cable 103, operate winding of relay OP-1 and thence to ground thereby causing relay OP-1 to operate and lock over the following circuit: Ground, locking winding, make contact and armature 104 of relay OP-1, conductor 105, conductor 5 of cable 106, make contact and armature 107 of relay LC-1 and thence to battery.

With range relay R3 operated and relays R1, R2 and R4 unoperated, a circuit is completed from battery on armature 99 and make contact of relay R3 through armature 108 and break contact of relay R2, conductor 4 of cable 101 through the winding of the range relay HI-1 and thence to ground causing relay HI-1 to operate and at its armature 109 and make contact thereof lock to battery on conductor 105 under control of relay LC1. A circuit is also completed from battery on armature 99 and make contact of relay R3, armature 108 and break contact of relay R2, conductor 111, break contact and armature 112 of relay R4, armature 113 and break contact of relay R1, conductor 114, conductor 5 of cable 101, winding of relay LO-1 and thence to ground thereby causing the range relay LO-1 to operate and lock by way of its contact and armature 115 to battery on conductor 105. Another circuit is completed from battery on armature 112 of relay R4 by way of conductor 116, conductor 6 of cable 101 to the winding of the range relay LA-1 and thence to ground thereby causing the range relay LA-1 to operate and lock through its contact and armature 117 to battery on conductor 105.

The unison range signals having the third code unit thereof marking in character have caused the operation of relay R3 of the group of range decoding relays. The operation of the relay R3 only of this group of relays, with the relay TR-1 operated, causes the range relays OP-1, HI-1, LO-1 and LA-1 of channel 1 to operate to select the indicators of the Open, High, Low and Last ranges respectively of a channel 1 stock for operation. If the quotation had been for a

stock on channel 2, relay TR-1 would have been unoperated and the corresponding range relays OP-2, HI-2, LO-2 and LA-2 would have been operated. The operation of the selected stock relay G and the range relays has closed the circuit in part for the operation of the indicators of the selected stock. The manner in which the indicator operating impulses are generated and applied to the selected indicators will presently be described.

When the distributor brush DB engages segment RLS-1 of ring R3, ground is applied to conductor 118 extending to the winding of relay RLS-1 thereby causing relay RLS-1 to be operated during the time that the distributor brush is passing over this segment of the ring R3. The operation of relay RLS-1 at its armature 58 removes battery from conductor 58 thereby causing relay R3 to release. The operation of relay RLS-1 at its armature 83 removes battery from one side of the locking winding of relay LC-1 thereby holding the gang relay G and the relay LC-1 operated after the distributor brush has left segment LC, the circuit extending from ground through the winding of relay G and make contact 88 thereof, contacts 89 of the slidable member 91, armature 93 and make contact of relay LC-1, locking winding of relay LC-1, break contact and armature 94 of relay CH-1 in parallel with the break contact and armature 71 of relay RLS and thence to battery.

The operation of relay LC-1 at its armature 119 applied battery to conductor 121 extending to one end of the winding of the restoration pulse relay PR from whence the circuit is continued through the winding of this relay by way of conductor 12 of cable 69 to segment 48 of the ring R1. The engagement of segment 48 by the distributor brush DB applies ground to conductor 12 of cable 69 causing relay PR to be operated during the time that the brush is in engagement with this segment thereby to cause the first restoration impulse to be transmitted to the selected indicators in the following manner. When armature 122 of relay PR engaged its make contact, battery was applied to armature 123 and make contact of relay TR-2, conductor 1 of cable 124, armature 125 and break contact of relay US-1, winding of relay A1, break contact and armature 126 of relay AA1 and thence to ground, the relays A1 and AA1 comprising the regenerator RGR-1 of channel 1, causing relay A1 to operate and lock by way of its make contact and armature 127 to battery. The operation of relay A1 at its armature 128 applied battery through resistance 129 to the winding of relay AA1 thereby causing relay AA1 to operate and at its armature 126 remove ground from the winding of relay A1 whereby relay A1 releases and at its armature 128 releases relay AA1.

When armature 131 of relay A1 engaged its make contact, battery was applied to conductor 1 of cable 132, armature 133 and make contact of relay OP-1, conductor 5 of cable 134, break contact of slidable member 91, contact 135 of the relay G, winding of the tens indicator of the Open range, contacts 136 and thence to grounded conductor 137 thereby operating the open tens indicator.

The release of relay A1 of the regenerator RGR-1 interrupted the circuit to the open tens indicator unit thereby causing the indicator to be stepped ahead to the next position in response to the first restoration impulse. When armature 137 of relay PR engaged its make con-

tact, battery was applied to armature 138 and make contact of relay TR-2, conductor 2 of cable 124 and thence to the winding of relay A2 of the regenerator unit RGR-2 thereby causing the operation of relay A2. When armature 139 of relay PR engaged its make contact, battery was applied to armature 141 and make contact of relay TR-2, conductor 3 of cable 124, extending to the winding of relay A3 of the regenerator RGR-3 thereby causing the operation of relay A3. Relays A2 and A3 when operated lock to battery and are released by the operation of relays AA2 and AA3 respectively in a manner similar to that of regenerator RGR-1.

When relay A2 operated battery at its armature 142 was applied to conductor 2 of cable 132, armature 143 and make contact of relay OP-1, conductor 6 of cable 134, contacts of slide member 191, contacts 144 of relay G, winding of the units indicator of the Open range and contact 136 thereof to grounded conductor 137 thereby operating the open units indicator and causing it to be stepped ahead to the next position when relay A2 releases. The operation of relay A3 at its armature 146 applied battery to conductor 3 of cable 132, armature 147 and make contact of relay OP-1, conductor 7 of cable 134, contacts of member 91, contacts 148 of relay G, winding of the fractions indicator of the Open range, contact 149 to grounded conductor 137, thereby advancing the fractions indicator one step in response to the first restoration impulse.

The operation of relay A1 at its armature 151 applied battery to conductor 4 of cable 132, armature 152 and make contact of relay HI-1, conductor 8 of cable 134, contacts of member 91, contacts 153 of relay G to the winding of the tens indicator of the High range from whence the circuit is continued through contact 154 of the indicator to grounded conductor 137 for actuating the high tens indicator in response to the first restoration impulse. The remaining tens, units and fractions indicators of each of the selected ranges of the stock 123 are operated by the regenerators RGR-1, RGR-2 and RGR-3 over circuit paths including operated contacts of the range relays HI-1, LO-1 and LA-1.

When the distributor brush engages segment 54 of the ring R1, ground is applied to conductor 12 of cable 69 to again operate the pulsing relay PR and the regenerators RGR-1, RGR-2 and RGR-3 and thus transmit the second restoration impulse to the selected indicators. When the distributor brush engages segments 60 and 66 of the ring R1 the third and fourth restoration impulses are transmitted to the indicators of the selected stock, the pulsing relay PR having operated to transmit four restoration impulses to the indicators of the stock selected during this first revolution of the distributor.

At the end of the first revolution of the receiving distributor RD the line relay LR is operated to move the armature thereof into engagement with contact S thereby applying battery to the start magnet SM and causing it to operate over a circuit including segment 1 of the ring R1, brush DB and grounded ring R2. The operation of the start magnet causes the armature 52 thereof to be attracted thus releasing the distributor brush for a second revolution. During this revolution the signals for a channel 2 quotation are received by the odd numbered segments of ring R1 or blank signals are re-

ceived, as the case may be. In the example assumed, since only one channel 1 quotation is to be received, during the second and subsequent revolutions of the receiving distributor only blank signals will be received.

When the distributor brush DB engages segment 4 of the ring R1 ground is applied to conductor 12 of cable 69 to cause the operation of the pulsing relay PR and regenerator units 10: RGR-1, RGR-2 and RGR-3 to transmit the fifth restoration impulse to the indicators of the selected stock. Similarly the sixth, seventh, eighth, ninth, and tenth restoration impulses are transmitted as the distributor brush engages segments 10, 16, 22, 28 and 34 respectively. When the distributor brush passes off segment 34 of the ring R1 all of the selected indicators will be on their blank positions with their windings disconnected from grounded conductor 137 and connected to conductors 155 or 156, both of which are ungrounded at this time.

When the distributor brush DB engaged segment CH of the ring R3, ground was applied to conductor 2 of cable 64, armature 165 and make contact of relay CH2, armature 165 and make contact of relay CH1, to one end of the winding 166 of relay CH1 from whence the circuit is continued through break contact and armature 66 of relay SYN to battery thereby energizing winding 166 of relay CH1 and causing relay CH1 to release by neutralization of the flux of the relay. The release of relay CH1 at its armature 67 interrupted the circuit through the winding 68 of relay CH2. Relay CH2, however, is held operated from battery through the other winding of the relay, break contact and armature 165 of relay CH1, make contact and armature 65 of relay CH2 to ground on conductor 2 of cable 64, the adjustment of the relays CH1 and CH2 being such that armature 165 of relay CH1 engages its break contact before armature 65 of relay CH2 is disengaged from its make contact. When the distributor brush passes off segment CH ground is removed from conductor 2 of cable 64 and relay CH2 releases. The release of relay CH2 at its armature 70 removes battery from conductor 14 of cable 69, thereby causing relay TR1, Fig. 1, to release.

When the distributor brush engaged segment 50: RLS of the ring R3, ground was applied to conductor 3 of cable 64 thereby causing relay RLS to operate and perform the same function in regard to a channel 2 quotation that it performed during the first revolution of the receiving distributor for a channel 1 quotation. However, since in the example assumed, blank signals only are received during the second revolution of the receiving distributor instead of signals for a channel 2 quotation, the operation of relay RLS at this time is without effect.

When the distributor brush engages segment TR of the ring R3 ground is applied to conductor 4 of cable 64, armature 73 and make contact of relay TR3, winding of relay TR2, make contact and armature 74 of relay TR3 which is connected to battery thereby causing relay TR2 to release and remove battery from one end of resistance 76, whereby winding 77 of relay TR3 is made ineffective after the brush has passed off segment TR. While the brush is in engagement with segment TR, ground on conductor 4 of cable 64 is applied through armature 90 and make contact to the winding 78 of relay TR3 thereby holding TR3 operated. When the brush DB passes off segment TR the locking circuit for relay TR3

is opened and relay TR3 releases. The release of relay TR3 at its armatures 158 and 159 applies ground to conductors 3 and 4 of cable 157, these circuits being continued through contacts 161 and 162 of the switching mechanism 91 and contacts 163 and 164 of the relay G, thereby applying ground to conductors 155 and 156 to condition the selected indicators for operation in response to the first actuation impulse to their windings.

The engagement of segment LC of the ring R3 by the brush DB applies ground to conductor 5 of cable 64, armature 79 and break contact of relay CH2 and thence to the winding of relay LC2, thereby causing relay LC2 to operate. Since there is no selection of a channel 2 relay G during this revolution of the distributor, in the example assumed, relay LC2 releases as the distributor brush passes off segment LC. The passage of the brush DB over the segment RLS-1 caused the relay RLS-1 to operate and release as the brush leaves segment RLS-1.

It will be recalled that when the distributor brush DB engaged segment RLS of the ring R3 during the second revolution of the distributor, relay RLS operated. The operation of relay RLS at its armature 68 and make contact thereof applied battery to conductor 13 of cable 69 thereby operating the trip magnet 27 of the overlap units SOU and POU.

The operation of the trip magnet 27 of the selection overlap units SOU is without effect at this time as no selection signals were received during this revolution of the receiving distributor. The operation of the trip magnet 27 of the price overlap unit POU causes the contact and reset bails to be set into operation to transfer the settings of the selection magnets corresponding to the price information during the first revolution of the receiving distributor to the associated contacts of the overlap unit and to be stored there until the selected indicators have taken their price settings. The timing of the price overlap unit is preferably such that the selected contacts thereof are closed during the time that the tenth restoration impulse is being transmitted to the indicators and remain closed until the distributor brush has passed segment 27 of the ring R1 during the next succeeding revolution of the distributor.

The pulsing relays P1, P2, P3 and P4, Fig. 1, are operated by certain of the even numbered segments of the distributor R1 when a stock has been selected in either channel of the display board, one or both of the relays LC1 and LC2 having locked in series with the selected stock relay G and thus applying battery to conductor 8 of the cable 69 extending to one end of the windings of the relays P1 to P4. When this condition is present, relay P1 operates to transmit seven pulses, relay P2 four pulses, relay P3 two pulses and relay P4 one pulse during one complete revolution of the distributor RD in accordance with the setting of the contacts of the overlap unit POU thereby to operate the regenerators RGR-1, RGR-2 and RGR-3 of channel 1 or channel 2, as the case may be, to cause the selected indicators to step from their normal positions to their new price settings.

With battery connected to conductor 8 of cable 69, relay P1 operates seven times, relay P2 four times, relay P3 twice and relay P4 once during a complete revolution of the distributor RD. The indicators are moved to their new price settings by a proper combination of impulses from

the ring R1 through the action of the pulsing relays P1 to P4 and the regenerator units RGR-1, RGR-2 and RGR-3. Since the overlap unit POU has taken a setting to post the price 98%, the tens indicator will receive seven pulses from relay P1 and two pulses from relay P3, the units indicator will receive seven pulses from P1 and one pulse from relay P4, and the fractions indicator will receive four pulses from relay P2, one from relay P4 and two from relay P3. The manner in which these impulses are transmitted to the selected indicators will now be described.

When the distributor brush DB engages segment 40 of the ring R1 during the second revolution of the receiving distributor, ground is applied to conductor 166 extending to the winding of relay P1 from whence the circuit is continued through conductor 8 of cable 69, conductor 121, make contact and armature 119 of relay LC1 to battery thereby causing relay P1 to be operated during the time that the brush is traversing segment 40. Since, in the example assumed, the relay P1 is employed to transmit actuation impulses to at least one of the selected indicators, the first actuation impulse is transmitted to the indicators from segment 40 of the ring R1.

Referring to Fig. 11 of the drawings, it will be noted that the code for the digit 9 comprises code units 1 and 3 marking in character and, since the contact of the overlap unit POU corresponding to the first unit of the code is connected to a contact of relay P1 and the contact of the overlap unit corresponding to the third unit of the code for the tens digit is connected to a contact of relay P3, the relays P1 and P3 are employed to transmit seven and two impulses respectively to provide nine impulses for actuating the tens indicator to display the digit 9.

When armature 167 of relay P1 engages its make contact, battery is applied to conductor 1 of cable 168, contact 169 of the price overlap unit POU, conductor 9 of cable 69, armature 171 and break contact of relay TR2, conductor 1 of cable 124, armature 125 and break contact of relay UF-1, winding of relay A1, break contact and armature 126 of relay AA1 and thence to ground, thereby causing the regenerator RGR-1 to operate and transmit the first actuation impulse to the tens indicators of the selected stock. When armature 172 of relay P1 engages its make contact, battery is applied to conductor 5 of cable 168, contacts 173 of the overlap unit POU, conductor 10 of cable 69, armature 174 and break contact of relay TR2, conductor 2 of cable 124 extending to the winding of relay A2, thereby causing the regenerator RGR-2 to operate and transmit the first actuation impulse to the selected tens indicators.

When the distributor brush DB engages segment 46 of the ring R1, the relay P1 again operates to transmit the second actuation impulse for causing the selected tens and units indicators to move to display their digits 2. When segment 50 of the ring R1 is engaged by the brush DB, ground is applied to conductor 175 extending to the winding of relay P2, thereby causing relay P2 to operate and apply battery to the conductors 2, 6 and 9 of cable 168. The circuits including conductors 2 and 6 of cable 168 are without effect as the associated contacts of the price overlap unit POU are open. The circuit is closed, however, from battery on armature 176 and make contact of relay P2, cable 168, conductors 177 of the price overlap unit, conductor 11 of cable 169,

armature 178 and break contact of relay TR2, conductor 3 of cable 124 extending to relay A3 of the regenerator RGR-3 thereby causing this regenerator to operate and transmit the first actuation impulse to the selected fractions indicators.

When the distributor brush engages segments 52, 58 and 64 of the ring R1, the third, fourth and fifth actuation impulses are transmitted to the tens and units indicators by the operation of the pulsing relay P1. As the distributor brush traverses segments 56 and 62 of the ring R1, the second and third actuation impulses are transmitted to the fractions indicators by the operation of relay P2, the tens and units indicators having received five actuation impulses and the fractions indicators three actuation impulses during this revolution of the receiving distributor.

When the distributor brush engages segment 2 of the ring R1 during the third revolution of the distributor, relay P1 operates to transmit the sixth actuation impulse to the tens and units indicators of the selected stock. The engagement of segment 6 of the ring R1 by the distributor brush causes the relay P2 to operate and transmit the fourth actuation impulse to the fractions indicators. When the distributor brush engages segment 8, the relay P1 operates to transmit the seventh actuation impulse to the tens and units indicators.

When the distributor brush engages segment 14 of the ring R1, ground is applied to conductor 179 thereby operating relay P4 to transmit the eighth actuation impulse to the selected units indicators and the fifth actuation impulse to the fractions indicators. When armature 181 of relay P4 engages the make contact thereof, battery is applied to conductor 11 of cable 168, contact 182 of the price overlap unit and thence to conductor 11 of cable 69, armature 178 and break contact of relay TR2, conductor 3 of cable 124, and thence to the fractions regenerator unit RGR-3, thereby operating regenerator RGR-3 and thus stepping the fractions indicators to display the digit 5.

When armature 183 of the relay P4 engages its make contact, battery is applied to conductor 8 of cable 168, contact 184 of the overlap unit POU, conductor 10 of cable 69, armature 174 and break contact of relay TR2, conductor 2 of cable 124 and thence to the units regenerator RGR-2, thereby operating the regenerator and causing the selected units indicators to be stepped ahead in response to the eighth actuation impulse to display the digit 8.

When the distributor brush DB engages segment 20 of the ring R1, ground is applied to conductor 185 thereby causing pulsing relay P3 to operate during the time that the distributor brush is in engagement with this segment. The operation of relay P3 at its armature 186 and make contact thereof applies battery to conductor 3 of cable 168, operated contacts 22 and 21 of the price overlap unit POU, conductor 19 of cable 69, armature 171 and break contact of relay TR2, conductor 1 of cable 124, armature 125 and break contact of relay UF-1 and thence to the winding of relay A1 of the regenerator RGR-1 thereby causing this regenerator to operate and transmit the eighth actuation impulse to the selected tens indicators. When relay P3 operated battery at its armature 187 and make contact thereof was applied to conductor 10 of cable 168, contact 188 of the overlap unit POU, conductor 11 of cable 69, armature 178 and

break contact of relay TR2, conductor 3 of cable 124, thereby operating the fractions regenerator RGR-3 and causing the selected fractions indicators to be stepped ahead in response to the sixth actuation impulse to display the digit 6.

When the distributor brush engages segment 26 of the ring R1, battery is applied to conductor 185 thereby operating pulsing relay P3 and the regenerators RGR-1 and RGR-3 to transmit the ninth actuation impulse to the selected tens indicators and the seventh actuation impulse to the selected fractions indicators respectively. The indicators of the Open, High, Low and Last ranges of the selected stock have now been set to post the price 97%.

When the distributor brush engaged segment SS during this third revolution of the distributor, relay SS operated and closed a circuit to the clutch trip magnet of the stock selector S but, since in the example assumed blank signals only are received during this revolution of the distributor, the operation of the selector S is without effect.

When the distributor brush engaged segment CH of the ring R3, ground was applied to conductor 2 of cable 64, armature 65 and break contact of relay CH2, winding of relay CH1 from whence the circuit is continued to the break contact and armature 66 of relay SYN to battery, thereby causing relay CH1 to operate and at its armature 67 apply ground from segment CH of the distributor to the winding 68 of relay CH2, the other end of which winding is also connected to ground. When the brush leaves the segment CH ground is removed from one end of the winding 68 of relay CH2 thereby causing relay CH2 to operate in series with relay CH1 over the following circuit:

Battery on armature 66 and break contact of relay SYN, winding of relay CH1, make contact and armature 61 of relay CH1, winding 68 of relay CH2 to ground. The operation of relay CH2 at its armature 70 applied battery to conductor 14 of cable 69 causing relay TR1 to operate and thereby disconnect the operate windings of the range relays of channel 2 from the range storage relays R1 to R4 and connect the range storage relays to the range relays of channel 1. Since only blank range signals are received during this revolution of the distributor, none of the range storage relays R1 to R4 or range relays of channel 1 will be operated.

When the distributor brush DB engages segment RLS of the ring R3, ground is applied to conductor 3 of cable 64 thereby causing relay RLS to operate during the time that the brush is in engagement with this segment. The operation of relay RLS at its armature 71 removes battery from the locking winding of relay LC1 thereby causing relay LC1 and the gang relay G of the selected stock to release. The release of relay LC1 at its armature 107 removes battery from conductor 5 of cable 106, extending by way of conductor 105 to the locking windings of range relays OP-1, HI-1, LO-1 and LA-1 thereby causing these range relays to release after all of the actuation impulses to the selected indicators have been received.

When the distributor brush engages segment TR of the ring R3, ground is applied to conductor 4 of cable 64 extending to armature 73 and break contact of relay TR3, winding of relay TR2, break contact and armature 74 of relay TR3 and thence to battery, thereby causing relay TR2 to operate and apply battery at its armature 75 and make

contact thereof to one end of the resistance 76. The other end of the resistance is connected to ground on conductor 4 of cable 64 by way of armature 90 and break contact of relay TR3. When the brush leaves segment TR ground is removed from conductor 4 of cable 64 thereby causing relay TR3 to operate from battery on armature 75 and make contact of relay TR2, resistance 76, winding 11 of relay TR3 and thence to ground. The operation of relay TR2 at its armatures 123, 138, and 141 connected the channel 1 regenerators to the contacts of the restoration pulsing relay PR. The pulsing relay PR is prevented from operation, however, as the distributor brush passes over the restoration segments since a gang relay G is not selected during this or the succeeding revolution of the receiving distributor and neither relay LC1 nor relay LC2 is operated at any time other than the time when the distributor brush is in engagement with segment LC of the ring R3 thereby removing battery from conductor 121 extending to the winding of relay PR.

The operation of relay TR2 at its armatures 171, 174 and 178 disconnects the regenerators of channel 1 from the contacts of the overlap unit POU and connects these contacts to the regenerators of channel 2. The channel 2 regenerators, however, are not operated over this circuit as all of the selection contacts of the price overlap unit are open and, furthermore, none of the pulsing relays P1 to P4 will operate to transmit impulses to the overlap unit POU as battery is not applied to one end of the winding of these pulsing relays by the operation of either relay LC1 or LC2 at a time when ground is applied to the other end of the windings of these pulsing relays by the brush DB.

When the distributor brush engages segment LC of the ring R3, ground is applied to conductor 5 of cable 64, armature 79 and make contact of relay CH2 and thence to the winding of relay LC1 thereby causing relay LC1 to operate and release as the distributor brush passes off segment LC. The operation of relay LC1 at this time is without effect. The engagement of segment RLS-1 by the distributor brush causes the operation of relay RLS-1 but since none of the range storage relays R1 to R4 are operated at this time and no gang relay G was selected for operation during this revolution of the distributor, the operation of relay RLS-1 is without effect.

The distributor now makes a fourth revolution causing relay SS to be operated by the engagement of the brush DB with segment SS of the ring R3 and the clutch trip magnet CTM of the stock selector S is operated but without effect since none of the stock selection magnets S1D to S3D are operated.

When the distributor brush engages segment CH, ground is applied to conductor 2 of cable 64, armature 65 and make contact of relay CH2, armature 165 and make contact of relay CH1, winding 166 of relay CH1, break contact and armature 66 of relay SYN and thence to battery thereby energizing winding 166 of relay CH1 and causing relay CH1 to release. Relay CH2 remains operated over a circuit including a break contact and armature 165 of relay CH1, make contact and armature 65 of relay CH2, conductor 2 of cable 64 and segment CH of the ring R3 until the distributor brush passes off segment CH and removes ground from this circuit thereby causing relay CH2 to release.

The engagement of segment RLS by the distributor brush causes the operation of relay RLS during the time the brush is in engagement with this segment.

When the distributor brush engages segment TR the relay TR2 releases and as the brush leaves segment TR, relay TR3 releases. When the distributor brush engages segment LC, ground is applied to conductor 5 of cable 64, armature 79 and break contact of relay CH2, winding of LC2 from whence the circuit is continued to battery, thereby causing relay LC2 to be operated during the time that the brush is in engagement with segment LC.

As the distributor brush engages segment RLS-1, ground is applied to conductor 118 thereby causing relay RLS-1 to operate during the time that the brush is in engagement with this segment and release as the brush leaves the segment. When the distributor brush has completed this revolution, it comes to rest in the position shown on Fig. 1 of the drawings as the tongue of the line relay is resting against its marking contact M at this time and the circuit to the distributor start magnet SM is therefore open, the distributor having now made 4 revolutions.

With the distributor at rest at the completion of the fourth or any even numbered revolution, the receiving apparatus is in condition to receive signals for a channel 1 quotation during the first succeeding revolution of the distributor. If, however, the first quotation to be transmitted is for a channel 2 stock, blank signals will be received during this first revolution of the distributor, the quotation signals for channel 2 being received during the second revolution thereof.

When the price to be posted does not require a change in the tens digit of the price, the tens indicator is prevented from operating by the operation of relay UF-1 or UF-2, as the case may be, which at its armature 125 interrupts the circuit to the tens regenerator unit associated with the channel with which the tens indicator is associated.

Referring now to Fig. 12 of the drawings, it will be noted that certain ranges; as for example, range Last (UF) comprise a code combination whereby the range relays R1 to R4 take settings such that battery is applied to conductor 1 of cable 101 extending to armature 189 of relay TR1 from whence the circuit is continued either through conductor 7 of cable 103 to cause the operation of relay UF-1 or through conductor 7 of cable 191 to cause the operation of relay UF-2 in accordance with the operated condition of relay TR1. Relay UF-1 when operated locks by way of its make contact and armature 192 to conductor 105, conductor 5 of cable 106 to which is applied battery by the operation of relay LC1 and relay UF-2 when operated locks by way of its armature 193 to conductor 7 of cable 106 to which battery is applied by the operation of relay LC2. When the new price has been posted the release of relay LC1 releases relay UF-1 and similarly the release of relay LC2 causes relay UF-2 to release.

Special stock posting

Certain stock postings require that four digits be posted in ranges other than close and that digits higher than 7 be posted in the fractions position. Whereas in the illustrative embodiment of the invention the prices of such stocks are transmitted on the second channel, it will be

understood that either channel may be employed for such transmission. To each such stock is assigned three selection numbers, each number comprising three digits and differing from the other two numbers only by the hundreds digit of the number. The three digits employed as hundreds digits are 6, 7 and 8.

The stock bar for such a stock differs from the other stock bars in that the first two lugs thereof corresponding to the first two code units of the hundreds stock digit are removed and the second two lugs are bent to their spacing positions, the second two lugs corresponding to the third and fourth code units of the hundreds stock digit. The remaining lugs are bent in accordance with the tens and units digits of the stock number and the channel of the stock. This stock bar, in so far as hundreds code digit is concerned, will move on hundreds digit 7 or 8 since the code for these numbers has code units 3 and 4 thereof spacing in character.

Whenever the received stock number has the hundreds digit 6, the third and fourth code units of the hundreds digit are both marking in character, and the selection overlap unit SOU is so arranged that neither the third nor fourth selection magnet of the stock selector is operated. When the second and third code units of the hundreds digit of the stock number, received and stored in the selection overlap unit SOU, are both marking in character, contact 194 is moved out of engagement with contact 195 and contact 196 is disengaged from contact 197, and the circuit between the first digit selection magnets S1D3 and S1D4 of the stock selector S and conductor 1 of the cable 69 is interrupted, thereby preventing the second and third selection magnets of the selector S from operating when battery is applied to this conductor. If the third or fourth code unit of the hundreds digit should be spacing in character, however, battery through contacts 195 and 194, or 197 and 196 would be applied to the third or fourth selection magnets of the stock selector, as the case may be. Therefore, when the hundreds digit 6 is received, although it comprises code units 3 and 4 marking, the stock selector code bars 3 and 4 corresponding to the selection magnets S1D do not move and the special stock bar will, therefore, be selected for operation.

This arrangement provides a stock bar which will operate on hundreds code 6, 7 or 8 provided the tens and units digits of the stock number received are in accordance with the tens and units digits formed in the bar. When hundreds code digit 6 is transmitted, the stock is selected in the manner of a regular stock. However, when hundreds code digits 7 or 8 are transmitted, the pulsing circuits are switched by the operation of relays RT and RT-1, Fig. 3. Each of these relays is operated by a stock bar which is so formed that the hundreds code 7 (1 marking, 2, 3 and 4 spacing) is employed for the RT bar and the hundreds code 8 (2 marking, 1, 3 and 4 spacing) for the bar RT-1. The tens and units lugs of both the RT and RT-1 bars are removed and the channelling lug is bent to the proper channel. Therefore, when either the hundreds digit 7 or 8 is transmitted on this channel, regardless of the tens and units digit of the stock number, one or the other of these bars will move and close their associated contacts.

When the RT bar 200 moves, relay RT operates

at the same time as the gang relay G over the following circuit: battery at armature 82 and break contact of relay RR1, armature 83 and break contact of relay RLS-1, conductor 7 of cable 69, armature 84 and break contact of relay CH2, armature 199 and make contact of relay LC-2, conductor 3 of cable 69, contact 201 of the bar 196, conductor 5 of cable 69, winding of relay RT, and thence to ground. The operation of relay RT at its armature 202 closes a locking circuit for the relay to conductor 203, make contact and armature 204 of relay LC-2 to battery thereby holding relay RT operated until after relay LC-2 has released.

The operation of relay RT at its armature 205 interrupts the circuit extending to the fractions regenerator AA3 of channel 2 by way of armature 206 and break contact of relay RT1 and conductor 6 of cable 124, thereby preventing the fractions regenerator from pulsing. When armature 208 of relay RT operates, the circuit of the tens regenerator unit of channel 2 is switched whereby this regenerator will respond to pulses transmitted over the units channel, the circuit extending now from the strapped contacts of the units selection contact of the price overlap unit POU, conductor 9 of cable 69, strapped contacts of the units selection contacts of the price overlap unit, conductor 10 of cable 69, armature 174 and make contact of relay TR2, make contact and armature 201 of relay RT, armature 211 and break contact of relay RT1, conductor 4 of cable 124 and thence to the tens regenerator unit of channel 2.

The operation of relay RT at its armature 203 disconnects the tens regenerator from the tens pulsing circuit and connects the tens pulsing circuit to the units regenerator whereby the units regenerator is operated over the tens channel, the circuit including conductor 9 of cable 69, armature 171 and make contact of relay TR2, conductor 4 of cable 106, armature and break contact of relay UF-2, conductor 2 of cable 106, make contact and armature 203 of relay R2, armature 209 and break contact of relay RT1, conductor 5 of cable 124 extending to the units regenerator of channel 2.

The operation of relay RT at its armature 212 disconnects the pulsing circuit from the units regenerator of channel 2 established over conductors 2, 5, 8 and 11 of cable 213 through the operated ones of the range relays CLS-2, OP-2, HI-2, LO-2 and LA-2 of channel 2 and certain of the conductors 3, 6, 9, 12 and 15 of cable 106 extending to armatures 212 of relay RT in accordance with the range relays which are operated at the time. With relay RT unoperated, these circuits are continued through the break contact of armatures 212 of relay RT to cause the operation of the units regenerators, one of the circuits, for example, including conductor 15 of cable 214 extending through operated contacts 215 of the slideable member 91, contacts 216 of the selected gang relay G and thence to the units indicator of the last range. With the relay RT operated this circuit is disconnected from conductor 15 and connected to conductor 5 of cable 214 extending through operated contacts 217 of the slideable member 91, contacts 218 of the relay G and thence to the hundreds indicator of the last range. The result of the operation of relay RT is to cause a price received on the tens and units channels to be posted on the hundreds and tens indicators respectively.

When the RT1 bar 219 moves the associated

contacts 221 are closed, thereby applying battery to conductor 4 of cable 69 and causing relay RT1 to operate and lock by way of its make contact and armature 222 of conductor 203, make contact and armature 204 of relay LC2 and thence to battery.

The operation of relay RT1 at its armature 211 interrupts the pulsing circuit to the tens regenerator of channel 2 and connects the tens pulsing circuit to conductor 5 of cable 134 extending to the units regenerator. The operation of relay RT1 at its armature 209 disconnects the units pulsing circuit from the units regenerator and connects the pulsing circuit to the fractions regenerator by way of conductor 6 of cable 124 and at its armature 206 interrupts the fractions pulsing circuit extending to the fractions regenerator. The result of this operation of relay RT1 is to post a price received on the tens and units channels on the units and fractions indicators whereby the fractions indicators may be set to any digit from 1 to 9 and 0. The result of this operation, briefly stated, is to post a price sent out as tens and units as units and fractions respectively.

The posting of a special price comprising four digits requires two transmissions, the first transmission causing the operation of relay RT and the posting of the hundreds and tens digits in accordance with the tens and units signals received whereas during the second transmission, relay RT1 is operated and causes the tens and units digits received to be posted in the units and fractions positions of the quotation board.

Posting yesterday's close

Yesterday's closing price includes the hundreds digit of the price, if any is to be posted, and when such is the case the full price of four digits requires two transmissions. During the first transmission the hundreds digit only is posted, the signal being received over the tens digit channel of the price accompanied by the range signal YCL (H), which comprises the unit 2 marking and code units 1, 3 and 4 spacing in character. With range code unit 2 marking, the line relay LR applies battery to conductor 53 extending to one end of the operate winding of relay R2, the other end of which is connected by way of conductor 4 of cable 56, segment 39 of the ring R1, distributor brush DB and thence to ground at the ring R2 thereby causing relay R2 to operate and lock under control of relay RLS-1. With relay R2 operated and relays R1, R3 and R4 unoperated, a circuit is completed from battery on conductor 6 of cable 69, conductor 96, armature 97 and break contact of relay R1, armature 98 and break contact of relay R4, armature 99 and break contact of relay R3, armature 223 and make contact of relay R2, conductor 1 of cable 101, armature 124 of relay TR1 and make contact thereof (in the case of a channel 1 quotation), conductor 1 of cable 103, winding of range relay CLH-1 and thence to ground thereby causing relay CLH-1 to operate and at its armature 125 close a circuit from the tens regenerator RGR-1 as follows: battery at armature 131 and make contact of relay A1, conductor 1 of cable 132, armature 125 and make contact of relay CLH-1, conductor 1 of cable 134 and thence through the contacts of member 91 and relay G to the hundreds indicator unit of the Yesterday's Close range, causing this indicator to operate and post the digit received over the tens digit channel in the hun-

dreds digit position of range YCL of the selected stock.

Operation of range relay CLH-1 at its armature 225 closed the circuit from the tens regenerator RGR-1 whereby the operation of relay A1 caused battery at armature 131 thereof to be applied to conductor 1 of cable 132, armature 225 and make contact of relay CLH-1, conductor 1 of cable 134, contacts 226 of the slideable member 91, contacts 227 of relay G and thence to the hundreds indicator unit of the "yesterday's close" range, thereby posting the price digit received over the tens channel in the hundreds position of "yesterday's close" price.

During the revolution of the receiving distributor in which the tens, units and fractions price digits are received, the range signal spacing, spacing, marking, marking corresponding to the range YCL (TUF) is received. This range signal causes the tongue of the line relay LR to be resting against its contact S during the time segments 37 and 39 of the ring R1 are crossed by the brush DB and against its contact M during the time that the brush is in contact with segments 41 and 43 of the distributor ring R1, thereby applying ground to conductors 5 and 6 of cable 56 and thus operating range relays R3 and R4 to battery on conductor 53. With range relays R3 and R4 operated and relays R1 and R2 unoperated, a circuit is closed from battery on conductor 96, armature 97 and break contact of relay R1, armature 98 and make contact of relay R4, armature 228 and break contact of relay R2, armature 229 and make contact of relay R3, conductor 2 of cable 101 and thence to the operate winding of range relay CLS-1 by way of armature 231, make contact of relay TR1 and conductor 2 of cable 103 thereby causing relay CLS-1 to operate and lock to conductor 105 and at its armatures 232, 233 and 234 complete circuits from the tens, units and fractions indicators of the range YCL by way of conductors 1, 2 and 3 of cable 132 extending to pulsing contacts of the regenerators RGR-1, RGR-2 and RGR-3 respectively. The tens, units and fractions price signals received thus cause the tens, units and fractions indicators of the range YCL to post this information in accordance with the numerical value of these signals.

Reposting the display board

If one or more of the receiving stations should fail to post quotations transmitted from the transmitting station for any reason, as for example, the failure of the incoming line 51 or the failure of the supply of power at the receiving station, the quotation board at the receiving station may be reposted, after the trouble has been corrected, to the exclusion of other receiving stations in the following manner. When the cause of failure has been corrected, it is the usual practice to notify the transmitting station to this effect and the operators at the transmitting station, after receipt of this information, proceed to transmit all of the quotations posted on the checkboard at the transmitting station in addition to the new quotations appearing upon the ticker tape. The quotations taken from the checkboard under these conditions are herein-after referred to as rewrite quotations and are each accompanied by a special rewrite signal.

This special signal comprises code units 1, 2 and 3 spacing, 4 marking and 5 spacing and is received by the receiving station on segments 27, 29, 31, 33 and 35 of the distributor ring R1 of

which, segments 27, 29, 31 and 35 are connected by way of conductor 2 of cable 56 extending to the operate winding of relay RR and segment 33 is connected by conductor 1 of cable 56 to the operate winding of relay RR1.

When the first, second, third and fifth code units received on segments 27, 29, 31 and 35 respectively are spacing in character, the tongue of the line relay is in engagement with its contact S during the passage of the distributor brush over these segments and battery is thus removed from conductor 53 thereby preventing the operation of relay RR. However, when the distributor brush engages segment 33 of the ring R1 the tongue of the relay LR is resting against its marking contact M and battery is therefore applied to conductor 53, thereby causing relay RR1 to operate. Assuming that the key RR is closed as an indication that the rewrite quotations are not to be posted on the receiving equipment, relay RR1 locks over the following circuit. Ground at contacts of key RR, locking winding, make contact and armature 344 of relay RR1, conductor 58, armature 59 and break contact of relay RLS-1 to battery. The operation of relay RR1 at its armature 82 removes battery from conductor 1 of cable 69 thereby preventing the operation of a stock relay G corresponding to the stock number signals received during this revolution of the distributor. The engagement of segment RLS-1 by the distributor brush DB causes the operation of relay RLS-1 which at its armature 59 removes battery from the locking circuit of relay RR1 thereby causing relay RR1 to release.

Should any of the code units 1, 2, 3 or 5 of the signal received on segments 27, 29, 31, 33 and 35 of ring R1 be marking in character, relay RR would operate and lock by means of its armature 345 and make contact to the operated key RR. The operation of relay RR at its armature 346 closes a circuit from battery to armature 83 and break contact of relay RLS-1 and conductor 1 of cable 69 thereby energizing the contacts of the stock selector S whereby a selected gang relay G may be operated by the selector at a time when relay RR1 is in the operated position and armature 82 thereof is not in engagement with its contact. If rewrite signals are to be posted, the key RR is open and relays RR and RR1 are prevented from locking, the relay RR1 releasing when the distributor brush passes off segment 33.

Synchronizing the receiver

It will be recalled that the first quotation received by the selector is on channel 1 and since the transmitting distributor invariably makes an even number of revolutions, the signals received during the last revolution of the receiving distributor before coming to rest for a period longer than the normal rest period of the distributor, relate to channel 2. Furthermore, the transmitter makes at least two blank revolutions before coming to rest to cause the selector to complete the actuation of the selected indicators.

Relays CH1 and CH2, together with relays TR1, TR2 and TR3 are employed in the selectors to take care of directing the quotations as received to the appropriate channel. These relays are unoperated at the beginning of the revolution of the distributor during which channel 1 signals are received, in other words, after the completion of a revolution in which channel 2 signals are received. Since the transmis-

sion of quotations can be interrupted for a period longer than the regular rest period of the distributor only at the completion of an even number of revolutions, these relays should always be unoperated when the distributor is thus stopped. If, however, for any reason the selector should be out of step with the transmitter when the transmission stops, these relays will be operated and cause relay SYN, Fig. 3, to operate over the following circuit. Ground on the rest segment of ring R3 of the distributor, conductor 1 of cable 64, make contact and armature 347 of relay CH1 and make contact and armature 348 of relay TR3 in parallel, winding of relay SYN to battery.

The operation of relay SYN at its armature 66 removes battery from the windings of relay CH1 thereby causing relays CH1 and CH2 to release. The release of relay CH2 at its armature 70 removes battery from conductor 14 of cable 69 thereby releasing relay TR1. When armature 66 of relay SYN engaged its make contact battery was applied to conductor 349 extending to winding 351 of relay TR2 thereby causing relay TR2 to release and at its armature 75 remove battery from winding 77 of relay TR3 causing relay TR3 to release. With relays CH1 and TR3 released, the circuit to the winding of relay SYN is open and relay SYN releases.

The receiving equipment is thus automatically brought into step with the transmitter and is now in condition to receive signals transmitted during the first revolution of the receiving distributor as channel 1 signals. It will be noted that relay SYN is slow operating and does not operate when the distributor comes to rest at the end of each odd numbered revolution as the distributor does not pause at that time for a period greater than the normal rest period.

Operation of auxiliary selector

The operation of the auxiliary selector and associated auxiliary stock board will now be described. Referring to Fig. 4 of the drawings and the apparatus and wiring at the bottom of Fig. 2, it will be noted that this equipment comprises three regenerator units RGR-1A, RGR-2A and RGR-3A together with a group of range relays CLH to LA for each of the two channels and relay RTA making a total of 13 relays and 6 regenerator units located preferably within the auxiliary selector cabinet. The auxiliary display board of Fig. 4 is similar to the main display board shown on Fig. 3. The number of stocks posted on the auxiliary board and the size thereof are entirely independent of the main board and may be made larger or smaller regardless of the size of the main display board.

The operation of regenerator RGR-1A is under control of the regenerator RGR-1 and the operation of regenerators RGR-2A and RGR-3A are under control of regenerators RGR-2 and RGR-3 respectively. When regenerator RGR-1 operates battery at armature 352 of regenerator RGR-1 is applied to conductor 1 of cable 353 and thence to the regenerator RGR-1A and when regenerators RGR-2 and RGR-3 operate battery is applied to conductors 2 and 3 of cable 353 to cause regenerators RGR-2A and RGR-3A respectively to operate. Thus each time regenerators RGR-1 to RGR-3 operate the corresponding regenerators of the auxiliary board RGR-1A to RGR-3A are caused to assume their operated positions. In a similar man-

5
nner the regenerators in the main selector employed for channel 12 quotations apply battery to conductors 4, 5 and 6 of cable 352 thereby operating the regenerators of the auxiliary selector to post the prices of channel 2 stocks by actuating the selected indicators thereof.

10
Cable 103 is extended to the auxiliary selector and conductors 1 to 6 thereof are connected to the windings of the auxiliary range relays of channel 1 and cable 191 is similarly extended to the auxiliary selector, the conductors 1 to 6 thereof being connected to the auxiliary range relays of channel 2. The range relays of the auxiliary selector are thus caused to operate whenever the corresponding range relays of the main selector operate, the auxiliary range relays of channel 1 locking by way of conductor 354 to conductor 5 of cable 106 to which battery is applied by the operated armature 107 of relay LC-1. The auxiliary range relays of channel 2 lock by way of conductor 355 and conductor 1 of cable 106, conductor 203, make contact and armature 204 of relay LC2 and thence to battery.

15
The stock relays GA of the auxiliary board are connected to the stock selector S, Fig. 1, by means of cable 92. The stock relay GA shown on Fig. 4 of the drawings, for example, is connected to conductor 1 of cable 92 and operates whenever the stock relay G of Fig. 3 operates. It will be understood, however, that the stock relays of the auxiliary board may operate independently of the stock relays in the main board and conversely the stock relays of the main board may operate independently of the stock selectors in the auxiliary board. When relay GA operates it closes a locking circuit for the winding of relay GA through its operated contacts 356, contacts of the slideable member 91A to conductor 1 or 2 of cable 92 in accordance with the position of the member 91A and thus locks in a manner similar to the G relays of the main display board.

20
The operate winding of relay RTA is connected by way of conductor 1 of cable 353 and conductor 5 of cable 69 to the winding of relay RT, both relays operating whenever contacts 201 are closed by the operation of the RT bar 200. Relay RTA when operated locks by way of its armature 356 to conductor 355 and releases when the range relays of the channel 2 group of the auxiliary selector release. The function of relay RTA is to switch the connection between the range relays and the indicator units of the auxiliary display board by the operation of its armatures 360 in a manner similar to the operation of relay RT at its armature 212.

25
The operation of relays RTA and RT occurs when selection signals are received which include signals corresponding to the digit 1 for the hundreds digit of the stock number. Relay RTA, therefore, operates only when signals for a stock number having the hundreds digit 1 are received and transposes the circuit connections in such a manner that signals received during the tens and units price portion of the message are transmitted to the hundreds and tens indicator units of the auxiliary stock board required for posting special information such as, for example, volume of sales. As this interchange of connections is not required when the units and fractions indicators of the auxiliary stock board are operated for displaying the units and fractions digits corresponding to special information, such as volume of sales, under control of a stock number

30
having the hundreds digit 8, relay RTA is unoperated during the setting of these indicators. The impulse circuits between regenerators RGR-1A, RGR-2A and RGR-3A and the channel 1 range relays CLH-1 to LA-1 include the conductors within cable 351 and the pulsing circuits between the channel 2 range relays CLH-2 to LA-2 include the conductors in cable 358.

35
The pulsing circuits between the channel 1 range relays and the auxiliary display board include the conductors within cable 359 and the pulsing circuits between the channel 2 range relays and the display board include the conductors in cables 361 and 362, the circuits being continued from the conductors of cable 362 to the conductors in cable 363 in accordance with the operated condition of relay RTA. The indicator operating circuits include grounded conductor 364 or the conductors in cable 157 in the manner of the arrangement of the main display board.

40
The lamps adjacent to the indicators of the high and low ranges shown on Figs. 3 and 4 of the drawings are operated by contacts of the high and low range relays whenever these relays are operated thereby to call attention to the fact that a new high or low price is being posted on the main and auxiliary boards. The circuits for the operation of these lamps are simple series circuits which will be readily understood from an inspection of the drawings without a detailed description of the circuits. The high and low lamps of the main display board are designated H and L respectively on the drawings and the high and low lamps of the auxiliary board are designated HA and LA respectively. It will be understood, of course, that these lamps may be provided with distinctive lamp caps or colored in any manner to produce a distinctive signal.

45
For purposes of illustration this invention has been described in connection with a stock quotation system but it is obviously not so limited, being adapted for use in various systems for the dissemination of information. Also, the embodiment of the invention may take other specific forms without a departure from the spirit or principle herein described. The present embodiment is, therefore, illustrative and not restrictive, the scope of the invention being indicated by the appended claims rather than by the foregoing description, and all changes within the meaning and range of equivalency of the claims are intended to be embraced therein.

50
What is claimed and desired to be secured by United States Letters Patent is:—

55
1. In a receiving apparatus, a source of signals comprising item selection and item information signals, a display board comprising a plurality of posting devices each including groups of indicators for displaying said item information, a distributor having segments for receiving said selection and information signals, a group of segments on said receiving distributor for generating indicator actuating impulses, means including a plurality of signal regenerative relays controlled by said group of segments, means for selecting any desired group of posting devices in accordance with the selection signals received, means for operating the posting devices of said display board by impulses from said signal regenerative relays when a group of posting devices has been selected by said selecting means and means for

invariably preventing the operation of said regenerative relays when selection signals are received which do not correspond to one of the items posted on said posting devices.

2. In a quotation system, a plurality of groups of electrically actuated indicators for posting information regarding stocks or other items, a source of quotation signals including item selection signals, means including distributor structure for receiving said signals, means controlled by the distributor for selecting any of said groups of indicators, regenerative means operated by the distributor for actuating the indicators selected by said selective means, and means for preventing the operation of said regenerative means as the distributor operates when selection signals are received which do not correspond to one of said selectable groups of indicators.

3. In a receiving mechanism for market quotations or other items, a source of signals including item signals, a receiving distributor having a group of segments for receiving said signals during one cycle of operation thereof, a plurality of posting devices each having a home position and a plurality of moved positions, a first group of segments with the individual segments thereof interspersed with the individual segments of the group of receiving segments, a second group of segments with the individual segments thereof interspersed with the individual receiving segments and the individual segments of said first group, storage means for storing the information signals received by said group of receiving segments during said one cycle of operation of the distributor, regenerative means actuated by the said first group of segments for restoring said devices to their home positions during said one cycle and a succeeding cycle of operation of the distributor, and means controlled jointly by the regenerative means and the second group of segments during said succeeding cycle of operation of the distributor for actuating said posting devices to their moved positions in accordance with the signals stored in said storage means.

4. In a system of the character disclosed, a source of quotation signals comprising selection and price signals, a rotary distributor having a first group of segments for receiving said signals during one revolution thereof, a plurality of groups of indicators for displaying the quotations, means for selecting during said one revolution of the distributor any of said groups of indicators under control of the selection signals received, means including a second group of segments with the individual segments thereof interspersed with the individual segments of said group of receiving segments for restoring to normal the selected indicators during said one revolution and a succeeding revolution of the distributor, and means including a third group of segments with the individual segments thereof interspersed with the individual segments of the first and second groups of segments for generating actuating impulses during said succeeding revolutions of the distributor to cause the indicators to display a quotation in accordance with the price signals received during said first revolution of the distributor.

5. In a receiving and retransmitting mechanism for market quotations or other items, a plurality of posting devices each adapted to be restored to a given position and then actuated to a new setting for displaying information in regard to certain of said items, a source of signals com-

prising information in regard to said items, a distributor having a group of segments for receiving in succession said item information signals and a group of impulse generating segments, the individual segments of either group being interspersed with the individual segments of the other group, storage means for storing said item information signals received by said receiving segments, means comprising said impulse generating segments for locally generating restoration impulses concurrently with the reception of said item information signals by said receiving segments, and means for restoring and actuating said posting devices in accordance with said restoration impulses generated and said information signals stored in said storage means.

6. In a receiving and retransmitting mechanism for market quotations or other items, a plurality of posting devices each adapted to be selected and restored to a given position and then actuated to a new setting for displaying information in regard to certain of said items, a source of signals comprising item selection signals and item information in regard to said items, a distributor having a group of segments for receiving in succession said item selection and information signals and a group of impulse generating segments, the individual segments of either group being interspersed with the individual segments of the other group, storage means for storing said item information signals received by said receiving segments, means comprising said impulse generating segments for locally generating restoration impulses concurrently with the reception of said item selection signals by said receiving segments, and means for selecting, restoring and actuating said posting devices in accordance with said item selection signals, restoration impulses generated and said information signals stored in said storage means.

7. In a receiving and retransmitting mechanism for market quotations or other items, a source of signals comprising item selection signals and item information in regard to said items, a plurality of posting devices each adapted to be selected and restored to a given position and then actuated to a new setting for displaying information in regard to certain of said items, a distributor having a group of segments for receiving in succession said item selection and information signals and a group of impulse generating segments, the individual segments of either group being interspersed with the individual segments of the other group, storage means for storing said item information signals received by said receiving segments, means comprising said impulse generating segments for locally generating restoration impulses concurrently with the reception of said item selection and information signals by said receiving segments, and means for selecting, restoring and actuating said posting devices in accordance with said item selection signals, restoration impulses generated and said information signals stored in said storage means.

8. In a receiving and retransmitting mechanism for messages comprising market quotations or other items, a plurality of posting devices each adapted to be restored to a given position and then actuated to a new setting for displaying information in regard to certain of said items, a source of signals comprising a first message and a second message in regard to said items, a distributor having a group of segments for receiving in succession the signals comprising said first

and second messages and a group of impulse generating segments, the individual segments of either group being interspersed with the individual segments of the other group, means comprising said impulse generating segments for locally generating restoration impulses during the reception of said second message by said receiving segments, for restoring the posting device on which said first message is to be posted, and means for actuating said posting device in accordance with said restoration impulses generated and said message signals received by said receiving segments.

9. In a receiving and retransmitting mechanism for messages comprising market quotations or other items, a plurality of posting devices each adapted to be restored to a given position and then actuated to a new setting for displaying information in regard to certain of said items, a source of signals comprising a first message and a second message in regard to said items, a distributor having a group of segments for receiving in succession the signals comprising said first and second messages and a group of impulse generating segments, the individual segments of either group being interspersed with the individual segments of the other group, means comprising said impulse generating segments for locally generating restoration impulses during the reception of said first and second messages by said receiving segments for restoring the posting device on which said first message is to be posted, and means for actuating said posting devices in accordance with said restoration impulses generated and said message signals received by said receiving segments.

10. In a receiving and retransmitting mechanism for messages comprising market quotations or other items, a plurality of posting devices each adapted to be restored to a given position and then actuated to a new setting for displaying information in regard to certain of said items, a source of signals comprising information in regard to said items, a rotary distributor having a

segmented ring comprising a group of segments for receiving in succession said item information signals and a group of impulse generating segments, the individual segments of either group being interspersed with the individual segments of the other group, a distributor brush adapted to engage said segments successively during a cycle of operation of the distributor, means comprising said distributor brush and said impulse generating segments for locally generating restoration impulses concurrently with the reception of said item information signals by said receiving segments, and means for restoring and actuating said posting devices in accordance with said restoration impulses generated and said information signals received by said receiving segments.

11. In a receiving and retransmitting mechanism for messages comprising market quotations or other items, a plurality of posting devices each adapted to be restored to a given position and then actuated to a new setting for displaying information in regard to certain of said items, a source of signals comprising information in regard to said items, means comprising a distributor having a segmented ring with a first group of segments for receiving in succession said item information signals and a second group of segments for locally generating impulses for restoring said posting devices and a third group of segments for locally generating impulses for resetting said posting devices to new settings in accordance with said item information signals, the individual segments of each group being interspersed with the individual segments of the other groups, and distributor brush structure adapted to engage said segments successively during a cycle of operation of the distributor, and means for restoring and actuating said posting devices in accordance with said restoration impulses and said resetting impulses generated.
